UNITED STATES PATENT OFFICE.

LILLIAN CALLAHAN, OF BROOKLYN, NEW YORK, ASSIGNOR TO H. R. MALLINSON & CO., INC., OF NEW YORK, N. Y., A CORPORATION OF NEW YORK.

DESIGN FOR A CUT-OUT DISPLAY DEVICE.

57,425.

Specification for Design.

Patented Mar. 29, 1921.

Application filed May 29, 1919. Serial No. 300,745. Term of patent 7 years.

To all whom it may concern:

Be it known that I, LILLIAN CALLAHAN, a citizen of the United States of America, and a resident of the borough of Brooklyn, city and State of New York, have invented a new, original, and ornamental Design for a Cut-Out Display Device, of which the following is a specification, reference being had to the accompanying drawing, showing my design.

The drawing shows a face view of a portion of a color display card embodying my design. While I have shown my design embodied in a color display card, I want it to be understood that the application of the design is not limited to color display cards,

as it may obviously be embodied also in sample cards, display boxes and other cut-out display devices.

The essence of my invention resides in the general appearance of the design, substantially as shown and described, and resembling the shape of a butterfly.

It is to be understood that my claim includes all substantial equivalents of my design, as shown and described.

I claim:

The ornamental design for a cutout display device, substantially as shown and described.

LILLIAN CALLAHAN.
